UNITED STATES PATENT OFFICE

110,117

DESIGN FOR A SKILLET

Albert M. Weis, Milwaukee, Wis.

Application April 8, 1938, Serial No. 76,379

Term of patent 14 years

To whom it may concern:

Be it known that I, Albert M. Weis, a citizen of the United States, residing at Milwaukee, in the county of Milwaukee and State of Wisconsin, have invented a new, original, and ornamental Design for a Skillet, of which the following is a specification, reference being had to the accompanying drawing, forming part thereof.

In the drawing:

I claim:
The ornamental design for a skillet, as shown.

ALBERT M. WEIS.
